UNITED STATES PATENT OFFICE.

GEORGES A. DE GUIRE, OF MONTREAL, QUEBEC, CANADA.

ELECTROMECHANICAL MOTOR.

1,296,634.

Specification of Letters Patent. Patented Mar. 11, 1919.

Application filed May 9, 1916. Serial No. 96,437.

To all whom it may concern:

Be it known that I, GEORGES A. DE GUIRE, a subject of the King of Great Britain, and a resident of Montreal, Quebec, Canada, (whose post-office address is 460 La Salle road, Verdun, Montreal, Quebec, Canada,) have invented new and useful Improvements in Electromechanical Motors, of which the following is a specification.

10 My invention relates to an electromechanical motor.

The present application is a continuation in part of application Ser. No. 11,652, filed Mar. 1, 1915.

15 In order to more clearly disclose the construction, operation, and use of my invention, reference should be had to the accompanying drawings forming part of this application. It is here shown as used in ring-

20 ing a bell. Throughout the several figures of the drawings like reference characters designate the same parts.

In the drawings:

25 Fig. 1 is a diagram, showing the relation of the parts and the connections;

Fig. 2 is an enlarged cross section of the solenoid coils showing the core inside and a front view of the rack;

30 Fig. 3 is an enlarged side elevation of the tripping mechanism;

Fig. 4 is an enlarged side elevation showing the contacts, the brushes and the flexible lead which carries the current to the brushes;

35 Fig. 5 is an enlarged cross section on line 5—5— of Fig. 1;

Fig. 6 is a side elevation of one of the coils;

40 Fig. 7 is an enlarged side elevation of one of the insulation plates between the coils;

Fig. 8 is a cross section on line 8—8 of Fig. 4;

Fig. 9 is a cross-section of square tube 21 of Fig. 4;

45 Fig. 10 is a cross section on line 10—10 of Fig. 4; and

Fig. 11 is a side view of one of the pins.

Referring to Fig. 1, a square tube 21 is mounted so as to slide through suitable guides 18 secured on frame 47. The upper portion of square tube 21 travels through a solenoid B which is composed of a number of coils a^1 to a^{14} mounted on a tube 19 and connected in series and spaced by sheets of non-conductive material 55 such as fiber, and carries a core 20 insulated from the square

tube 21 by non-magnetic material 48 secured thereto and to the core 20. On the lower end of the square tube 21 are mounted brushes 22 and 23 in brush holders 52 insulated by non-conductive material 50 and secured by screws 51. The upper end of square tube 21 is connected by means of an eye bolt 29 to a rope 41 fastened on the usual pulley 43 for operating bell 44 in the usual manner. A counter weight 46 of sufficient weight to counterbalance the square tube 21 and the members carried thereby, is secured to the end of rope 42 to insure accuracy of operation of the bell 44. The coils 70 of solenoid B, a^1 to a^{14} are connected by suitable conductors 1^a to 15^a to a series of contacts 1 to 15. These contacts are mounted on the frame 47 on centers which correspond in spacing to the spacing of solenoid 75 coils B. These contacts 1 to 15 are connected to coils a^1 to a^{14} as follows: Contact 1 is connected by conductor 1^a to coil a^1 . Contact 2 is connected by conductor 2^a to coils a^1 and a^2 . Contact 3 is connected by 80 conductor 3^a to coils a^2 and a^3 . Contact 4 is connected by conductor 4^a to coils a^3 and a^4 . This method of connections being continued throughout for a purpose to be later disclosed.

When the system is in its normal condition, the pawl 25 of the tripping switch is pointing down and lever 26 is raised and the upper end 27 of the sliding rod 39 is hooked to the lower end of armature 45 90 which keeps contacts 24 closed. If now, this circuit is connected to a suitable source of electric energy 30 and controlling switch 31 is closed, a current will flow therethrough and through two of the coils of the solenoid B.

Referring more particularly to Fig. 1, which represents more diagrammatically the operation of starting a bell in the ordinary manner; the square tube 21 carries two brushes 22 and 23 insulated from square tube 21 by non-conductive material 50. To the brushes 22 and 23 are connected flexible leads 33 and 34 fastened on frame 47 by an insulator 54. When the brushes 22 and 23 are in the normal position, that is as shown in Fig. 1, current flows from positive side of the source of electric energy 30, through conductor 35, conductor 17, contacts 24, conductor 34, brush 23, contact 11, conductor 11^a, coils a^{11} and a^{12} , conductor 13^a, contact 13, brush 22, conductor 33, switch 31

to negative of the source of electric energy 30. The flow of current through coils a^{11} and a^{12} produces a magnetic field around these coils. The core 20 is so placed in this 5 field that a maximum pull is exerted upon it by this field. The core 20 moves downward carrying the tube 21 and brushes 22 and 23 with it at the same speed. As the brushes 22 and 23 move downward on to succeeding contacts, the electric current is cut off from coil 10 a^{11} and coil a^{13} is cut in so that the magnetic field moves in the same direction and at the same rate as the core 20. When brush 22 reaches contact 16, current will flow from 15 positive side of the source of electric energy 30 through conductor 35, conductor 32, magnet 28, conductor 36, contact 16, brush 22, conductor 33, switch 31 to negative of the source of electric energy 30. This causes 20 magnet 28 to attract armature 45 which releases catch 27 and the expansion of spring 56 causes pawl 25 to rise and take a horizontal position and contacts 24 are open, thus stopping the flow of current in the 25 solenoid coils and the pull ceases. The bell 44 on its return swing pulls the core 20 and parts connected to it upward. During this movement the pin 40^a, which is the top one in the square tube 27 slides past the pawl 25 30 which is raised and kept at rest against the pressure of a light spring 37. When the downward swing again begins, one of the pins 40 engages pawl 25 which raises lever 26, engages catch 27 to catch of armature 35 45, and contacts 24 are closed. It will be noticed that the catches are made on a bevel. This is to allow the spring 38 to force rod 39 to raise lever 26 so that pawl 25 will clear the pins 40 on the downward motion. Coils 40 are then energized and a downward pull is exerted on the core 20 again until brush 22 reaches contact 16 as before described. This 45 cycle of motions will continue as long as current is supplied.

45 The operation of the tripping switch may be more clearly understood by reference to Fig. 3, which shows the tripping switch secured to frame 47 by bracket 53 in the position it would have when brush 22 is on contact 16. Armature 45 is attracted by magnet 28, the catch 27 is released, and spring 56 forces rod 39 to be thrown down, contacts 24 are opened, and pawl 25 is raised by lever 26 which engages rod 39. Suppose now, the 50 core 20 to be for the first time on its downward motion and brush 22 reaches contact 16, pin 40^a which is at the top in the square tube 21, is down far enough to clear pawl 25. Now the current through the coils 55 a^{13} and a^{14} is cut off by the opening of contacts 24. The length of movement increases with each stroke until the length of stroke desired has been reached. The length of stroke is determined by the number of coils 60 in the solenoid B. The number of pins 40

in the square tube 21 is determined by the length of stroke. The side of tube 21 which faces pawl 25, is cut away above the pins 40 the full length of stroke so as to clear the pawl 25 after it has been caused to 70 rise when brush 22 passed on contact 16. At each return motion of the bell 44 and tube 21 with its members carried thereby, one of the pins 40 engages pawl 25, closing contacts 24 which causes the coils to be energized as hereinbefore described. 75

The arrangement is such that the movement of the core 20 and the movement of the magnetic field which actuates the core 20 is simultaneous. 80

The speed of the reciprocating motion of the core when attached to a bell rope is controlled by the bell itself. That is, whether fast or slow, uniform or not uniform, or as in the case of a bell, approximately simple 85 harmonic, the core 20 and consequently the moving magnetic field follow properly the motion of that to which the motion is transmitted.

Changes may be made in the construction, 90 arrangement, and disposition of the various parts of the invention, within the limits of the appended claims, without in any way departing from the field and scope of the invention, and it is meant to include all such 95 within this application wherein only one form of the invention has been disclosed in order to clearly illustrate the same.

Having thus fully described my invention, what I claim as new and desire to secure by Letters Patent is: 100

1. A solenoid composed of separate coils, in combination with a core movable endwise therein, a part moving with said core, a succession of conductors, each having a 105 terminal bifurcated to connect with two of said coils, except the first and last of said conductors which connect with one coil each, a series of contacts corresponding to the series of coils and connecting respectively 110 with the conductors therefrom, a pair of brushes carried by said movable part and adapted to shift from contact to contact of said series with said motion to cut out and cut in the coils successively, circuit connections from said brushes adapted to be connected to a source of electricity, a movable circuit opener included in said circuit and comprising a notched sliding rod, an armature constructed to act as a catch for said 115 rod, an electro-magnet arranged to act on said armature for releasing the said rod, a contact additional to the series above stated, on the said movable part movable with the core and connected to the last of said conductors, and a branch circuit from the source of electricity through said magnet to the last mentioned contact, in order that the solenoid may be entirely cut off from the 120 source of electricity by the action of said 125

circuit opener when one of said brushes reaches said additional contact.

2. A solenoid composed of a series of separate coils and a fixed tube on which they 5 are fastened and which projects beyond the ends of said series of coils, in combination with a part of greater length than said tube and movable endwise through the same, a magnetic core on said part within said sole-
10 noid for causing such endwise movement, guides for said part, brushes carried by said part, a series of contacts for said brushes corresponding to said coils in number and arrangement with an additional contact,
15 connections from said brushes adapted to be connected to a source of electricity, a movable contact for opening and closing circuit between said source of electricity and said solenoid, means for maintaining said con-
20 tact in closed-circuit position, an electro- magnet for releasing said means, a branch circuit from said source of electricity through said magnet to the additional contact of said series, and electrical connections from said
25 contacts of said series to said coils of the solenoid substantially as described.
3. A solenoid composed of separate super- posed coils connected in series, a set of contacts from said coils adapted to be con-
30 nected to a source of electricity, in combination with a core for said solenoid, a movable part carried thereby, brushes carried by said part for electric connection with said contacts successively, a movable automatic
35 circuit opening device between said sole- noid and said source of electricity, means for catching said device and holding the same in closed position, means for freeing said device for such opening at stated in-
40 tervals, a device operated by said movable part and having sufficient momentum to slightly raise the latter and said core by its reaction, a series of pins carried by the first named movable part, a pawl arranged to permit the passage of the pins in one direc-
45 tion, but to be actuated by any of them

moving in the other direction, and a lever mechanically connecting said pawl to said movable circuit opening device for moving the latter under the action of any one of 50 said pins to close the circuit.

4. An electro-mechanical motor of the character described, comprising a solenoid composed of a plurality of separate coils, a core operative therein, circuits connecting 55 the aforesaid coils in series, means controlled by the aforesaid core and conductively connected to said coils, to successively energize and deenergize said coils, means for automatically breaking the circuit through the 60 solenoid when the desired stroke of said core is ended, means for automatically lifting the core and devices for closing the circuit again, comprising means actuated by said core and means coöperating therewith, a part 65 of the circuit closing devices being adapted to yield when the core moves in one direction and adapted to be moved to close the circuit when the core moves in the other 70 direction.

5. An electro-mechanical motor of the character described comprising a solenoid composed of a plurality of separate coils, a core operative therein, circuits connecting 75 the aforesaid coils in series, means controlled by the aforesaid core and conductively connected to said coils to successively energize and deenergize said coils, means for automatically breaking the circuit through the 80 solenoid when the desired stroke of said core is ended, means for automatically lifting the core, and means for closing the circuit again, comprising a pawl which will yield when the core moves in one direction and which will be moved to close the circuit when the 85 core moves in the other direction and pins arranged to coöperate with said pawl in producing the above result.

Signed at Montreal, Quebec, Canada, this 5th day of May, 1916.

GEORGES A. DE GUIRE.
